SHOE POLISH KIT OR SIMILAR ARTICLE

Robert M. Haygeman, 224 3rd St., Baraboo, Wis.

Filed Nov. 5, 1959, Ser. No. 58,223

Term of patent 14 years

(Cl. D58—12)

Fig. 1

Fig. 2

Fig. 3

Fig. 4

FIG. 1 is a top view of the cover of my new design for a shoe polish kit or similar article.

FIG. 2 is a side view of my new design for a shoe polish kit or similar article, showing the cover in place on the lower portion of the container.

FIG. 3 is a bottom view of my new design.

FIG. 4 is an end view of my new design showing the cover in place on the lower portion of the container.

I claim:

The ornamental design for a shoe polish kit or similar article, as shown.
